(57) **CLAIM**

The ornamental design for a syringe, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a first embodiment of a syringe showing my new design;

FIG. 2 is a front view of the first embodiment of the syringe;

FIG. 3 is a right side view of the first embodiment of the syringe;

FIG. 4 is a rear view of the first embodiment of the syringe;

FIG. 5 is a left side view of the first embodiment of the syringe;

FIG. 6 is a top view of the first embodiment of the syringe;

FIG. 7 is a bottom view of the first embodiment of the syringe;

FIG. 8 is a perspective view of a second embodiment of the syringe;

FIG. 9 is a front view of the second embodiment of the syringe;

FIG. 10 is a right side view of the second embodiment of the syringe;

FIG. 11 is a rear view of the second embodiment of the syringe;

FIG. 12 is a left side view of the second embodiment of the syringe;

(Continued)

FIG. 13 is a top view of the second embodiment of the syringe;

FIG. 14 is a bottom view of the second embodiment of the syringe;

FIG. 15 is a perspective view of a third embodiment of the syringe;

FIG. 16 is a front view of the third embodiment of the syringe;

FIG. 17 is a right side view of the third embodiment of the syringe;

FIG. 18 is a rear view of the third embodiment of the syringe;

FIG. 19 is a left side view of the third embodiment of the syringe;

FIG. 20 is a top view of the third embodiment of the syringe; and,

FIG. 21 is a bottom view of the third embodiment of the syringe.

The broken lines showing in the figures are included for the purpose of illustrating portions of the syringe that form no part of the claimed design.
